PILE FABRIC

Frank Sudell, Philadelphia, Pa., assignor to
La France Industries, Philadelphia, Pa., a corporation of Pennsylvania

Application February 18, 1939, Serial No. 257,228

2 Claims. (Cl. 139—391)

This invention relates to textile fabrics of the pile-face type, such as carpets, rugs, bath mats, stool covers, etc., including, for example, articles of the types disclosed in my prior U. S. Patent No. 2,144,555, dated January 17, 1939, wherein a base fabric of substantially plain weave commonly employed in the making of canvas or heavy duck is provided with longitudinally extending pile yarns spaced apart a substantial 5 distance laterally, and formed into longitudinally extending rows of pile tufts respectively which spread laterally until the tips of the marginal filaments of the laterally spaced rows of pile tufts lie substantially in abutting relation to each 10 other and cover relatively narrow areas of non-pile fabric lying intermediate the rows of pile tufts and give the surface of the fabric a more or less corrugated or wavy appearance. Under normal conditions of use, the marginal filaments 15 of adjacent rows of pile tufts occasionally become separated to some extent and expose the base fabric between the rows, which more or less detracts from the esthetic effect of the pile face as a whole, particularly in articles where the 20 base fabric is of a different color from the pile, which is normally the case, the base fabric usually being unbleached or of a neutral color, while the pile tufts are of any desired color intended to blend with other furnishings or 25 draperies of the room in which the fabric is used.

The object of the present invention is to provide a fabric of the general type noted above, wherein the yarns which form the pile tufts float across the normally non-pile areas lying intermediate the rows of pile tufts and cover the neutral colored base fabric at all points intermediate the rows of pile tufts, thus eliminating any and all exposure of the base fabric between the pile tufts should displacement of the pile 30 tufts along the marginal edges thereof occur.

The present invention more particularly relates to a fabric of the type noted but with the rows of pile tufts definitely spaced apart a sufficient distance to provide open or non-pile areas 35 between the rows of pile tufts at all times, and wherein the pile yarns float across the non-pile areas intermediate the rows of pile tufts and cover the neutral base fabric, resulting in a fabric having a face composed of laterally spaced rows 40 of cut pile tufts alternating with narrow non-pile areas composed of the same yarns as the pile tufts, which gives the face of the fabric a spaced bar appearance. The twisted yarn of the floats in the non-pile areas will reflect the 45 light rays differently from the cut ends of the yarn filaments in the rows of pile tufts.

In the fabric disclosed in said prior patent, the rows of pile tufts extended longitudinally, i. e. warpwise of the fabric, whereas in the fabric 50 of the present instance the rows of pile tufts

extend transversely, i.e. weftwise of the fabric, with the pile yarn floats between the transverse bars extending warpwise of the fabric and hiding the underlying base fabric.

The pile tufts, according to the present invention, may be of the V type or of the W type, without departing from the spirit of the invention. 5

In the accompanying drawings:

Fig. 1 is a plan view of a swatch of fabric made 10 in accordance with the principles of the present invention;

Fig. 2 is a longitudinal or warpwise sectional view taken on the line 2—2, Fig. 1;

Fig. 3 is a view similar to Fig. 2 and showing a 15 slightly modified arrangement with the pile tuft rows spaced a greater distance apart than in the fabric of Fig. 2;

Fig. 4 is a longitudinal sectional view showing the fabric of Fig. 3 as being woven double, prior 20 to splitting in a median plane intermediate the upper and lower fabrics;

Fig. 5 is a view similar to Fig. 3 showing one form of W type tuft;

Fig. 6 is a view similar to Fig. 4, illustrating 25 the weaving of the fabric of Fig. 5;

Fig. 7 is a view similar to Fig. 5, showing a somewhat different arrangement of the W tufts; and

Fig. 8 is a view similar to Fig. 6, showing the 30 manner of weaving the fabric of Fig. 7.

As shown in Fig. 2, the base fabric 1 is of the ordinary plain weave commonly employed in the making of heavy duck and comprises the usual series of transversely extending weft threads or 35 filling-shots 2, 2 bound together in the usual one and one weave by binder threads or warp chains 3, 3.

Interwoven with relatively spaced groups 4, 4 of the weft threads or filling threads 2, 2 are 40 pile warp threads 5, 5, which are disposed in close laterally abutting relation to each other, as shown in Fig. 2. The pile warps 5, 5 are formed into pile tufts 6, 6, with two or more tufts preferably arranged in succession longitudinally 45 of the fabric and cooperating with similar tufts formed from the laterally abutting pile warps to collectively produce transversely extending rows or bars 7, 7 which alternate with open non-pile areas 8, 8 on the pile face of the fabric. 50

Extending from one bar 7 to the next adjacent bar 7 across the open spaces 8, 8, are floats 9, 9. These floats 9 are formed of the pile warps 5, 5 and cover the underlying areas 10, 10 of the base fabric 1 which are composed of groups of weft 55 threads 2, 2, lying intermediate the groups 4, 4 of the weft threads with which the pile warps 5, 5 are interwoven to form the tufts 6, 6 of the transverse bars or ribs 7, 7.

From the above it will be clear that the spaces 60

8 between the rows or courses 7 of pile tufts are bridged by floats 9 of the pile forming warp threads 5 arranged in close laterally abutting relation to each other and covering the base fabric 1, thus giving the face of the fabric a very attractive appearance.

Fig. 3 illustrates a similar fabric to that shown in Figs. 1 and 2, with the exception that the bars or rows 7a, 7a are respectively wider than those shown in Figs. 1 and 2 but are composed of V tufts 6a, the same as the tufts 6 of Figs. 1 and 2. The spaces 8a in the fabric of Fig. 3 are considerably wider than the spaces 8 of the fabric of Figs. 1 and 2 and are also wider in proportion to the widths of the bar 7a, 7a, which makes the floats 9a of the pile threads 5a considerably longer than the floats 9 of the pile threads 5 of Figs. 1 and 2. The areas 10a of the base fabric 1a which lie intermediate the groups 4a, 4a of the wefts 2a, 2a around which the pile tufts 6a, 6a are formed, are correspondingly wider than the areas 10 of the base fabric 1 in Figs. 1 and 2. In the fabric of Fig. 3 the wefts 2a are tied together in pairs by the binder or warp chains 3a, 3a. The general effect of the fabric of Fig. 3 is, therefore, the same as the general effect of the fabric shown in Fig. 1, except as to the greater spacing of the rows or bars of pile tufts and the greater width of each bar or row of pile tufts.

30 In order to insure against the ends of the floats 9a being pulled loose, the pile yarns 5, 5 are interwoven with a plurality of the wefts 4a, 4a, at each of the opposite sides of each row of pile tufts, as indicated at 19a, 19a, in Fig. 3.

35 Fig. 4 shows the fabric of Fig. 3, as being woven double, i. e. with one complete fabric B superimposed above a corresponding fabric A, with a space C therebetween, the two fabrics being separated, after weaving, by cutting the pile yarns 5a, 5a on a median plane x, x equidistant from the fabrics A and B, said cutting on the line x, x producing the cut pile tufts 6a, 6a, which would be the same in each of the fabrics A and B respectively.

45 In the fabrics shown in Figs. 1, 2, 3, and 4, the simple form of V type tuft is produced, i. e. relatively short portions of the pile yarns 5 or 5a of which the pile tufts 6 or 6a are formed, pass under single weft threads or filling shots 2 or 2a, whereas in the fabrics shown in Figs. 5, 6, 7 and 8 the W type of tuft is provided, i. e. the yarn portion forming each tuft passes under one weft thread 2b, as shown in Fig. 5, over the next weft thread 2b, and then under a third weft thread 2b, 55 to produce the pile tuft 6b with the free ends of the piece of yarn projecting upwardly beyond the base fabric 1.

The opposite ends of each of the longer pieces or sections of the pile yarns 5b which constitute the floats 8b are interwoven with a plurality of wefts 2b, to secure these opposite ends of the floats against being pulled out during normal usage of the fabric.

As shown in Fig. 6, each pile yarn 5b associated with the lower fabric A1 is interwoven with a number of the weft threads 2b of the lower fabric, and then passes upwardly across the space C1 between the fabrics A1 and B1 into the fabric B1 where it is interwoven with a plurality of the wefts 2b of the upper fabric B1, as indicated at 15b. It then passes downwardly again across the space C1 into the lower fabric A1 where it is interwoven with a plurality

of the wefts 2b of the lower fabric A1, as indicated at 19b. In a similar manner each of the pile warps 5b of the upper fabric B1 is interwoven with a plurality of the wefts 2b of the upper fabric B1, then passes downwardly across the space C1 into the lower fabric A1, and is interwoven with a plurality of the wefts 2b of the lower fabric, as indicated at 15b. The pile warp then passes upwardly again across the space C1 into the fabric B1 where it is interwoven with a 10 plurality of the wefts 2b of the upper fabric B1, as indicated at 19b.

The pile warp yarns 5b, 5b, in the upper and lower fabrics B1 and A1 float in the space C1 adjacent the upper and lower fabrics respectively, as indicated at 9b, 9b, between the places where the yarns pass from one to the other of the upper and lower fabrics.

When the two fabrics are separated as disclosed above by splitting the doubly woven fabric on a 20 median plane midway between the fabrics A1 and B1, the lower fabric, in each of the transversely extending pile tuft bars 7b, will include a W tuft formed of the pile yarn normally interwoven with the upper fabric and two part 25 tufts 10b formed of the pile yarn normally, interwoven with the lower fabric, while the upper fabric B1, in each of the bars 7b, will include a W tuft formed of the pile yarn 5b, which is normally associated with the lower fabric A1 30 and two part tufts, corresponding to the part tufts 10b of the lower fabric, composed of the pile yarn normally associated with the upper fabric B1.

Figs. 7 and 8 show fabrics similar to Figs. 5 and 6 respectively, with a slight variation in the manner in which the yarns 5c, 5c of the upper and lower fabrics B2 and A2 respectively are led from the one to the other of the fabrics across the space C2 therebetween, the pile tufts in this instance being of the W type, the same as in the fabrics of Figs. 5 and 6, the tuft parts in the fabrics of Figs. 7 and 8 in some instances passing between two adjacent wefts 2c, 2c instead of at opposite sides of the wefts as shown in Figs. 45 5 and 6; otherwise, the fabrics are substantially the same.

I claim:

1. A textile fabric comprising a base fabric composed of interwoven warps and wefts, pile 50 warps interwoven with predetermined wefts at relatively spaced points warpwise of the fabric and formed into pile tufts projecting above one face of the base fabric in transversely extending longitudinally spaced continuous rows of substantially equal uniform width, with said pile warps floating warpwise of said fabric continuously on and covering said base fabric in the spaces between said rows of pile tufts.

2. A textile fabric comprising a base fabric 60 composed of interwoven warps and wefts, pile warps interwoven with predetermined relatively spaced groups of said wefts and formed into pile tufts projecting from said groups of wefts upwardly above one face of said base fabric in 65 longitudinally spaced continuous rows of substantially equal uniform width, with non-pile areas therebetween, said pile warps floating continuously on and covering said face of said base fabric between said relatively spaced rows of pile 70 tufts and interwoven with other predetermined wefts adjacent said groups of wefts.

FRANK SUDELL.
